(57) **CLAIM**

The ornamental design for a modular conduit cable management assembly, as shown and described.

DESCRIPTION

FIG. 1 is an exploded perspective view of a first configuration of a modular conduit cable management assembly, showing my new design;

FIG. 2 is another exploded perspective view thereof;

FIG. 3 is a top plan view thereof, with the bottom plan view being a mirror image thereof;

FIG. 4 is a front elevation view thereof, with the rear elevation view being a mirror thereof;

FIG. 5 is a left side elevation view thereof, with the right side elevation view being a mirror image thereof;

FIG. 6 is a section view thereof;

FIG. 7 is an exploded perspective view of a second configuration of the modular conduit cable management assembly of FIG. 1;

FIG. 8 is another exploded perspective view of FIG. 7;

FIG. 9 is a top plan view of FIG. 7, with the bottom plan view being a mirror image thereof;

FIG. 10 is a front elevation view of FIG. 7;

FIG. 11 is a rear elevation view of FIG. 7;

FIG. 12 is a left side elevation view of FIG. 7;

FIG. 13 is a right side elevation view of FIG. 7;

FIG. 14 is a section view of FIG. 7;

FIG. 15 is an exploded perspective view of a third configuration of the modular conduit cable management assembly of FIG. 1;

FIG. 16 is another exploded perspective view of FIG. 15;

FIG. 17 is a top plan view of FIG. 15, with the bottom plan view being a mirror image thereof;

FIG. 18 is a front elevation view of FIG. 15, with the rear elevation view being a mirror thereof;

FIG. 19 is a left side elevation view of FIG. 15, with the right side elevation view being a mirror image thereof; and,

(Continued)

FIG. 20 is a section view of FIG. 15.
